PORTABLE ELECTRIC SANDER

Robert O. Ernest, Oak Park, Ill., assignor to Sunbeam Corporation, Chicago, Ill., a corporation of Illinois

Application September 13, 1955, Serial No. 37,902

Term of patent 14 years

(Cl. D37—1)

FIG. 3.

FIG. 4.

Fig. 1 is a side view of a portable electric sander embodying my new design;

Fig. 2 is a top plan view of Fig. 1;

Fig. 3 is a front elevational view of the sander of Fig. 1; and

Fig. 4 is a rear elevational view of Fig. 3.

I claim:

The ornamental design for a portable electric sander, substantially as shown.
